UNITED STATES PATENT OFFICE.

LAWRENCE W. LUellen, OF BOONTON, NEW JERSEY, ASSIGNOR TO INDIVIDUAL DRINKING CUP COMPANY, OF NEW YORK, N. Y., A CORPORATION OF MAINE.

RECEPACLE.

1,308,793.

Specification of Letters Patent.

Patented July 8, 1919.

Application filed February 16, 1912. Serial No. 678,096.

To all whom it may concern:

Be it known that I, LAWRENCE W. LUellen, a citizen of the United States, residing at Boonton, in the county of Passaic and

5 State of New Jersey, have invented certain new and useful Improvements in Receptacles, of which the following is a full, clear, and exact specification.

My invention relates to certain new and 10 useful improvements in receptacles, and especially to that class of articles which are designed for but a single use. To prevent reuse or to render it unlikely, it is desirable that the articles should be susceptible of easy 15 destruction in so far as their utility as a container is concerned. In addition it is necessary that the receptacle should be comparatively cheap so that it can be economically discarded after use, and at the same time it 20 must possess the necessary strength, be of a sanitary character, and, when intended to contain liquids, waterproof.

My invention is intended to fulfil these requirements and as shown consists of a receptacle which is cheap to manufacture, possess the necessary strength, is sanitary, waterproof, and so easily destructible that any substantial distortion thereof will destroy or impair its usefulness.

30 While my invention may be embodied in various ways, I have here illustrated it as a drinking cup which is intended for a single use, and whereof two modified forms are shown in the drawings.

35 Figure 1 is a top or plan view of a drinking cup embodying my invention.

Fig. 2 is a side elevation thereof.

Fig. 3 is a fragmentary view of a portion of the cup at one stage in its process of manu- 40 facture; and

Fig. 4 a similar view at a later stage of manufacture.

Fig. 5 is a fragmentary side elevation similar to Fig. 2, but shows a flange upon the 45 cup.

Fig. 6 is a top plan view of the cup shown in Fig. 5.

Fig. 7 is a top view of a completed cup of modified form.

50 Fig. 8 is a side elevation thereof.

Fig. 9 is a fragmentary view of such cup at one stage in its process of manufacture.

Fig. 10 is a similar view at a later stage of manufacture.

55 Fig. 11 is a side elevation, partly broken

away, of a flanged cup similar to Fig. 8; and Fig. 12 is a top plan view thereof.

Similar numerals of reference indicate like parts in the drawings.

In the forms shown in Figs. 1 to 6, the cup 60 is formed of a single sheet of paper or other fibrous material, the blank being of circular shape and the center being utilized as the bottom 1, of the cup. The side walls are formed in part by folding or plaiting the material of the outer portion of the blank, such plaits being indicated at 2, as shown in Figs. 65 3 and 4. These plaits are of tapering character, increasing in width upwardly, and the exact form or shape of the plaits varies ac- 70 cording to the size, shape, and general contour of the receptacle desired. They may be first formed as shown in Fig. 3, either by hand or by suitable machinery, and in the case of a cup of the configuration shown, the 75 plaits or folds start from the bottom and increase in width until the overlapping portions are contiguous at the top. When the plaits are formed they are subjected to pressure, which results in their assuming sub- 80 stantially the position of arrangement shown in Fig. 4.

Either before or after the formation of the plaits as shown, the material is coated or 85 impregnated with paraffin, wax or other similar cementing material. Paraffin possesses the properties of being clean and sanitary and it is also waterproof. In addition it possesses adhesive properties sufficient to cement the plaits or folds in the side walls of 90 the cup together, and they thus constitute reinforcing ribs which add considerably to the strength of the cup and permit of the use of comparatively thin paper or fibrous material in the manufacture of the cup, thus keeping 95 the cost thereof very low.

It is a characteristic of paraffin or similar material applied in fused condition to the cup, that it will permeate the fibers of the paper, and where two or more thicknesses of 100 paper occur will be drawn through from one layer of the paper to the next succeeding layer by capillary attraction, a portion of the paraffin remaining between the layers of paper and serving to cement the layers 105 together as above indicated. In this way the desired cementing action is secured without the necessity of physically inserting the cementitious material between the layers of paper, which would greatly increase the 110

labor and cost of production. The paraffin permeating the paper tends to stiffen the same and when cold to render the structure somewhat brittle, and at the same time is not 5 a very strong adhesive so that any substantial distortion of the cup, such as pinching the side walls of the cup, causes the cup to crack or break along the vertical lines of single thickness between the plaited portions 10 or reinforcing ribs of the side walls of the cup, or causes the paraffin between the plaits to give way thus releasing or separating the plaits. In this way the usefulness of the cup is materially impaired and it is clearly indicated 15 to the observer that the cup has been previously used. After a single use of my cup, the user can simply pinch, squeeze, or crush the cup, thereby destroying its usefulness and indicating clearly that it has been used and is not to be used again by others. 20 In using the word "destroyed," I do not, of course, necessarily mean complete physical destruction, but merely the destruction or serious impairment of the usefulness of the 25 cup. I prefer to use a water-proofing, stiffening and cementitious material which is fusible, as paraffin, as the same can be readily applied, hardens quickly, and makes a most satisfactory water-proofing substance. 30 It is also a characteristic of such fusible materials, which have a comparatively low melting point, that they vary somewhat in rigidity, being less rigid and therefore not so likely to crack at ordinary room temperatures but becoming more rigid when cooled. 35 As my invention is particularly applicable to a cup for use with ice water or other cooled drinks, it will be seen that the cup will become more rigid when filled. This is desirable, 40 as it requires more force to hold the filled cup, and therefore greater rigidity is needed at that time. On the other hand, the cup, before filling, is not so rigid as to be brittle and may, therefore, be handled and 45 dispensed without danger of injury.

When to be used as a drinking cup I preferably provide my receptacle with a narrow projection, flange or lip at the upper rim. This may be formed over molds, or in any 50 other suitable manner. The molds serve to press the folds of material in the flange upon each other in which position they are held by the paraffin or other binder. The flange or lip adds considerably to the normal strength 55 of the article, and the cementing of the folds together in the flange holds the cup as firmly in shape, as is desirable. The fact that, as in the preferred form of my invention, the edges of the adjacent folds are substantially 60 contiguous results in the production of a flange of practically uniform thickness, and the flange being narrow will not interfere with the use of the cup for drinking purposes. In addition to its strengthening function 65 the flange is of importance as providing

means for dispensing the cups by suitable apparatus, such as that shown in my Patent No. 1,081,508. The flanges made in the manner described are sufficiently stiff to cooperate properly with the dispensing means such 70 as shown in my patent referred to, this result being further promoted by making the flanges narrow. The cup as a whole, however, has sufficient flexibility to permit the same to be withdrawn through a contracted 75 opening as described in said patent, and also permits the cups to be properly used in a dispensing device, such as shown in my Patent No. 1,043,854. The flanges are preferably not folded sharply out from the walls of the 80 cup, but are slightly curved or rounded, as shown in Figs. 5 and 11, thereby avoiding sharp creasing or breaking of the paper at that point and so weakening the flanges. The maximum strength of the flanges is thus 85 obtained for cooperation with the cup dispensing means.

In some instances, I prefer to make my cups of an inverted, truncated cone shape, as shown in Figs. 2 and 8, although this is 90 not essential, and the walls may be straight from end to end. In either case the preferred tapered shape and substantially smooth surface produced by pressing and cementing the folds in position, produces a 95 cup capable of nesting freely with similar cups to form a stack, thereby adapting the cups for compact and convenient storage and making them particularly suitable for use in dispensing devices such as described 100 in my patents above referred to.

The use of a fusible cement or coating, as mentioned above, also tends to produce a cup particularly applicable for use with such vending and dispensing devices, as the slight 105 increase in flexibility which occurs at moderate temperatures is desirable.

In the form shown in Figs. 1 to 6, the side walls of the cup are shown provided with simple folds or plaits and these will be 110 found satisfactory for many purposes. In some cases, however, I prefer to form them with box plaits, such as are shown in Figs. 7 to 12, as by this means a smoother-surfaced article may be produced and one possessing great strength.

In a number of the claims I have referred to the material used for coating the cup or cementing the parts in position as paraffin, but I do not intend by the use of this term 120 to limit myself only to substances which may be chemically designated by that name, but I intend to include equivalent waxlike substances, or substances having substantially 125 the characteristics which will permit the same to permeate the paper and render the cups sanitary, waterproof, sufficiently rigid for use and at the same time readily destrucible.

It is obvious that my invention may be 130

embodied in many ways and forms and I do not mean to limit myself to the particular forms shown and described, but what I claim and desire to secure by Letters Patent is:

5 1. As a new article of manufacture, a paper drinking cup made of a single piece of paper having its side walls formed by folding the paper upon itself, coated and impregnated with paraffin, the paper being cemented in folded position by the paraffin.

10 2. As a new article of manufacture, a paper drinking cup having its side walls formed by folding the paper upon itself to 15 form plaits, the plaits being pressed down and the cup coated with a sanitary, waterproofing, permeating coating which cements the plaits in position so as to form reinforcing ribs for the cup.

20 3. As a new article of manufacture, a destructible receptacle formed of a single piece of paper, the side walls of the receptacle being formed by folding the paper upon itself to form plaits tapering from the top toward 25 the bottom of the receptacle, the plaits being pressed down so as to give the cup a substantially smooth surface, and a coating of fusible, cementitious material of slight adhesive properties on the receptacle, making 30 the same waterproof and holding the plaits in position, and forming them into reinforcing ribs to strengthen the side walls of the cup.

4. As a new article of manufacture, a 35 paper drinking cup formed of a single piece of paper, the center of the blank forming the bottom of the cup and the outer portion of the blank being folded upon itself to form a plaited outwardly tapered side wall, 40 the size of the blank, the size of the bottom, and the taper of the side wall being so proportioned that the edges of the plaits will be substantially contiguous at the top of the cup, the plaits being pressed flat and held 45 in position by a fusible cementitious binder so as to form an easily destructible cup having a substantially smooth three-ply rim.

5. As a new article of manufacture, a paper drinking cup formed from a single

blank of paper, the bottom being formed 50 from the center of said blank and the side walls being provided with folds, the edges of which are substantially contiguous at the top of the cup, the rim of the cup being turned outwardly to form a flange, said 55 folds being secured in place by paraffin and the cup reinforced by paraffin.

6. As a new article of manufacture, a frusto-conical paper drinking cup formed from a single sheet of paper, the side walls of which are provided with folds or plaits formed from the surplus material of the blank, said 60 folds or plaits reinforcing and strengthening the side walls of the cup and terminating in an outwardly directed rim at the top, 65 said folds of the rim being held together and reinforced by paraffin.

7. A drinking cup having a side wall formed of paper folded upon itself to present a multiplicity of closely associated narrow folds capable of maintaining the wall in predetermined outline when the folds are secured together, said wall merging into an outwardly extending lip portion, and a 70 strengthener and binder of paraffin applied to the cup, cementing the layers of the folds together and continuing along the folds at the side of the cup, through the lip portion thereof, and around the junction therebetween, to stiffen the same.

8. As a new article of manufacture, a 75 drinking cup formed of a single piece of paper and having a tapered side wall including superimposed layers of the paper impregnated with and held together by a fusible cement.

9. A paper drinking cup made from a one piece flat blank of paper and having a rim formed by a plurality of layers of the paper reinforced with paraffin between and uniting the layers.

In witness whereof I have hereunto set my hand in the presence of two subscribing witnesses.
